UNITED STATES PATENT OFFICE

149,767

DESIGN FOR AN ELECTRIC CLOCK

Adolph J. Nelson, Oak Park, Ill., assignor to Rubber Products, Inc., Chicago, Ill., a corporation of Illinois

Application June 6, 1947, Serial No. 139,488

Term of patent 14 years

(Cl. D42—7)

To all whom it may concern:

Be it known that I, Adolph J. Nelson, a citizen of the United States, residing at Oak Park, in the county of Cook and State of Illinois, have invented a new, original, and ornamental Design for an Electric Clock, of which the following is a specification, reference being had to the accompanying drawing, forming part thereof.

Fig. 1 is a front view of an electric clock, showing my new design; and

Fig. 2 is a side view of same.

I claim:

The ornamental design for an electric clock, substantially as shown.

ADOLPH J. NELSON.
